(57) **CLAIM**

The ornamental design for a shelving system and cable management system, as shown and described.

DESCRIPTION

FIG. 1 is a perspective view of a shelving system and cable management system, showing my new design;

FIG. 2 is a front elevation view thereof;

FIG. 3 is a left side elevational view thereof, the right side being a mirror image thereof; and,

FIG. 4 is a top plan view thereof.
